UNITED STATES PATENT OFFICE.

HENRY H. GERKEN, OF NASHUA, IOWA.

FENCE-POST.

1,160,709.

Specification of Letters Patent. Patented Nov. 16, 1915.

Application filed March 10, 1915. Serial No. 13,405.

To all whom it may concern:

Be it known that I, HENRY H. GERKEN, a citizen of the United States, residing at Nashua, in the county of Chickasaw and 5 State of Iowa, have invented a new and useful Fence-Post, of which the following is a specification.

This invention relates to improvements in fence posts, and more particularly to that 10 class of posts to which may be readily attached the ordinary poultry or other wire fabric fencing without the necessity of using any nails, staples or similar fastening devices and without requiring special tools 15 therefor and with the same ease and readiness the fence may be detached from the post leaving the wire fabric in an unimpaired condition.

A further object is to provide a post, of 20 simple structure, which will securely hold the fence in a taut condition above the ground at a predetermined elevation, and to effectually prevent any sagging or lengthwise creeping or moving of the same.

25 A full and complete understanding of the invention may be obtained from a careful consideration of the following detailed description, taken in conjunction with the accompanying drawing forming a part of 30 this specification; it being understood that while the drawing shows a practical form of the invention, the latter is not confined to strict conformity therewith, but may be changed or modified, so long as such changes 35 or modifications mark no material departure from the salient features of the invention as specifically pointed out in the claim hereto appended.

In the drawing, in which like reference 40 characters designate corresponding parts in each of the several figures, Figure 1 illustrates, in perspective, the fence post supporting a woven wire fence. Fig. 2 is an edge view thereof. Fig. 3 is a detail sectional view on the line 3—3 of Fig. 1.

The fence post of the present invention 45 consists of the section 1 of ordinary angle or L-shaped iron such as is in common use, and cut of any length desired to suit the varying 50 widths of poultry wire or other woven wire fabric as indicated by the reference numeral 2 in the drawing. While the drawing illustrates the invention supporting a fence of the "mesh" type, it is to be understood that 55 the invention is equally well adapted to support wire fences of any style, as for in-

stance those having a series of line or strand wires at varying distances apart and vertically disposed stay wires secured thereto.

One face 3 of the post 1 is provided with 60 a plurality of outstanding hooks 4 formed by punching or severing the top, bottom and one side of a rectangular opening 5 in alternate arrangement, in order to permit of the tongues thus formed being bent outwardly 65 at an acute angle to the adjacent face 3 to form right and left hand hooks, the ends of the tongues being partially returned toward the face 3, as shown at 6, in such manner as to receive a vertically disposed tie rod 7 70 and support the same in spaced relation to the face 3 of the fence post 1. This space, as indicated more clearly at 8 in Fig. 3 of the drawing, is necessary in order to accommodate the several strands or line wires of 75 the fence to be supported on the post.

The tie rod 7, which is formed of ordinary 80 commercial wire of relatively heavy gage, is cut at a suitable length to extend from approximately the ground line, to the top 85 of the post, and is there provided with a return portion 9 to form a hook of sufficient length to engage the top edge of the face 3 and to prevent the rod 7 from slipping downwardly, while the hooks 4 act to prevent the said rod 7 from moving to the right or the left, thus holding the tie rod rigidly 90 against one face of the wire fence 2 and securely binding the same to the adjacent face of the fence post.

In the attachment of the particular fence shown in the drawing, to the device of the present invention, it will be seen that the uppermost hook 4 projects immediately beneath the upper selvage wire 12 of the fence 95 2 and thus acts as a support to prevent any downward movement thereof, while the lowermost hook 4 projects immediately above the lower selvage wire 13 of the fence 2 and, in the same manner, acts to prevent any 100 upward movement of the fence.

With the plurality of outwardly extending hooks 4, as provided on the post 1, there will always be a number of said hooks to engage directly under some of the line wires 105 of the fence, no matter what style the latter may be, and act as a support for the same.

In applying a fence to the post of the present invention, it is only necessary to run the former, in a taut condition, along the 110 face of the angle iron post provided with the hooks, and then slide the tie rod through

the said hooks, from top to bottom and on the opposite side of the wire fence to the post, until the hooked end of the tie rod engages the upper edge of the adjacent face of the post.

From the foregoing it will be seen that a simple, easily manufactured and inexpensive fence post has been devised, that is adapted to have a wire fence easily and quickly applied thereto or removed therefrom.

What is claimed is:—

A flanged metal fencepost provided on one of its faces with a plurality of spaced outwardly extending, alternating right and left hand horizontally disposed hooks, formed by partially severing the metal of said face, and then forcing the tongue thus formed

outwardly, and partially returning the end of the tongue toward the adjacent face of the post, and a tie rod adapted to be passed downwardly through the said hooks and held in spaced relation to the said face and having its upper end provided with means for engaging with the post to prevent the tie rod from dropping downwardly, the spacing of the rod from the face of the post permitting a wire fence being retained by the rod against the post.

In testimony, that I claim the foregoing as my own, I have hereto affixed my signature in the presence of two witnesses.

HENRY H. GERKEN.

Witnesses:

FRANK J. GERKEN,
A. L. KORTH.
